DREDGE BUCKET

William H. Stires, High Bridge, N. J., assignor to
Taylor-Wharton Iron & Steel Company, High
Bridge, N. J., a corporation of New Jersey

Application December 18, 1934, Serial No. 758,117

1 Claim. (CL 37—141)

My invention relates to dredge bucket and lip assemblies and provides novel and simple means for seating the lip in interlocking relation with the bucket so that it may be applied or removed with facility and dispatch.

More specifically stated, the invention provides certain improvements in swingingly mounted lips of the type set forth in my Letters Patent No. 1,984,322 whereby the seating of the lip is externally of the bucket and has no parts projecting inside the bucket likely to catch or trap spoil. Otherwise stated, the object is to provide for swinging the lip externally of the bucket so that it will constitute an extension flush with the inside of the bucket. The external seating of the bucket has the further merit that it overcomes certain foundry difficulties, particularly the saving of a lot of contour grinding in that the respective seating portions are finished in a substantially common plane. Furthermore, the new assembly has the further merit that by swinging the lip externally of the bucket, the capacity of the latter is considerably augmented.

The nature, characteristic features and scope of the invention more readily will be understood from the following detailed description taken in connection with the accompanying drawing, forming a part hereof, wherein:—

Figure 1 is a central vertical section of a dredge bucket and lip assembly embodying my improvements.

Fig. 2 is a section on line 2—2, of Fig. 1.

Fig. 3 is a sectional detail of the front lock, and

Fig. 4 is a section on line 4—4 of Fig. 1.

According to the invention the dredge bucket 5 is provided with a rim seat 6 to accommodate the shouldered portion 7 of a lip 8, and at the front and on the sides there are abutments 9

and 10 formed with open slots or channeled portions 11 to accommodate a continuous skirt or apron extension 12 of the lip. It will be noted that the abutting surfaces of the rim seat and the seating shoulder of the lip are finished in a substantially common plane. The purpose and effect of this is to simplify grinding and to insure a flush joint between the lip and the rim so that for all practical purposes the medial portion of the lip is a prolongation of the smooth flaring bowl. The skirt of the lip terminates rearwardly in crook-like arms 13 which are upwardly directed and are designed to engage bosses 14 on the wall of the bucket and below its rim seat. The boss and lip relationship stated is useful because it facilitates the application of the lip and because it serves to lock the ends of the lip through the intervention of the headed extremities 15 of the bosses.

The front lock may be of any approved type notwithstanding that I prefer the lock shown in Fig. 3, according to which a forked member 16 on the lip is adapted to cooperate with a lug 17 on the front abutment 9, the parts having registered openings to accommodate a wedge fastening 18.

Having described the invention, I claim:—

A dredge bucket having an uninterrupted smooth inner surface terminating in a rim whose edge wall defines a lip seat, a lip having a medial shouldered portion which fits the rim seat and having an outside lapping portion, means externally of the bucket and engaging the lapping portion of the lip to take the thrust thereof, bosses formed externally of the bucket and the lip having trailing ends adapted and arranged for swingingly engaging said bosses.

WILLIAM H. STIRES.
